SELF CONTAINED VAPOR ENGINE

Elmer F. Knowles, Battle Creek, Mich.

Application February 20, 1931. Serial No. 517,275

5 Claims. (Cl. 219—38)

The present invention has relation to vapor generating engines in which the vapor is intermittently generated coordinate with the action of the valve for operating the cylinder. In the present 5 instance, I have shown my invention as applied to the reciprocating type of steam engines, however it will be understood that the principle could be applied to rotary and other forms of engines wherein compression by vapor is used for motive 10 power.

In the present instance characteristic features of the invention are; first, a steam generating drum attached directly to the steam chest of a reciprocating steam engine, the steam being generated at each intake opening of the engine valve; second, a heating element carried within said generating drum whereby the water is instantly turned into superheated steam at each stroke of the engine piston; third, means whereby control 15 of the water for generating steam, will be automatically governed according to the power required of the engine; and fourth, means, including a thermostat communicating with the steam generator, whereby heat for operating the heating element will be governed according to the heat required.

The main object of the present invention, is to provide a device of the nature that will be very simple, or self contained, efficacious in operation, 30 and one that will require no especial furnace and boiler attendant, these and other objects and advantages, will hereinafter, be readily comprehended by an ordinary artisan, and by those familiar with steam engineering in particular.

35 In the drawings forming a part of the present specifications,

Fig. 1 represents my improved type of vapor producing apparatus applied to a reciprocating steam engine, the engine being in side view.

40 Fig. 2 is a plan view of Fig. 1.

Fig. 3 is a rear end view of the vapor generating drum, as positioned on the steam chest of the engine.

45 Fig. 4 is an enlarged longitudinal section of the water supplying dropper, for the steam generating drum.

50 Fig. 5 is a detail side section of the steam generating drum, and shows the water supplying dropper in a position for dropping a predetermined amount of water onto the heating chamber within said drum.

Fig. 6 is a cross section of Fig. 5, on the line 6, 6.

55 Fig. 7 is an enlarged end view of a carbon and its insulated air conductor.

Fig. 8 is an enlarged detail side view of the thermostat operated electrical control lever, and Fig. 9 is a plan view of the same.

In the drawings, like marks of reference refer to corresponding, or equivalent parts throughout the drawings, in which, A, as a whole, represents 60 an ordinary horizontal steam engine; B, my improved vapor generating drum; C, a safety valve attached near one end of the drum; D the heat generating chamber.

The vapor generating drum B, is seated directly upon the steam chest 1, of the engine cylinder 2, and is secured by cap screws 3, to said drum, in a customary manner.

Within the drum, a concentrically affixed heat 70 generating chamber D, is placed. As shown, this chamber is annularly corrugated for the purpose of affording contraction and expansion from heat produced therein, and from intermittent dropping of water thereon, for generating steam. For 75 heating the chamber, in this instance, I have shown carbons 5 entering through the drum and into the heat producing chamber from diametrically opposites, the same being supplied by electrical current by wires 6, operating from a dy- 80 namo, or other electrical source of supply. The carbons afford arcs of flame in a customary manner. It will be understood, that in lieu of electrically flaming carbons, that resistance coils, or flame produced by gas, or other means could 85 answer for the purpose.

Upon the top of the generating vapor drum B, a water gun 7, is placed for dropping water upon a center portion of the heat producing chamber D. Steam generated in the said drum, 90 passes into the steam chest 1 through a port opening 8. In passing the steam directly from the generating drum to the steam chest, loss of energy is conserved, owing to condensation being eliminated, so likewise, steam is conserved by not 95 carrying the same through piping, the latter of which not only forms a chamber in which expansion and compression may take place, but also, being exposed to air conditions, superheating of the steam is greatly lessened.

100 The water dropping gun 7 carries a reciprocating plunger 9 operated from a variable governor 10 on the engine shaft 11. As shown, the plunger has a transverse hole 12, through its rear extremity. The size of this hole is regulated by means 105 of a screw 13, screw-threaded into the end of the plunger so as to enter the hole 12, and which by turning the screw said hole may be increased or diminished in capacity, as desired. This gun at its rear end has a removable screw plug 14, 110

by which the screw 13, of the plunger may be readily gotten at for regulation. The gun on the under side is formed with a centrally apertured boss 15, adapted to seat in a corresponding 5 threaded bracket 16, attached to the vapor generating drum B.

Within the aforesaid boss, a small drip pipe 17 is screw-threaded. This pipe extends downwardly into the vapor chamber 18 of the drum 10 in such a manner that water dropping from the gun will be directed on a central upper line of the heat generating chamber D, and in close proximity to the flame produced by the carbons in the heating chamber.

15 Opening into the small chamber to the rear of the plunger of the gun 7, a small vent hole 19 is located, to avoid a vacuum.

Near the inner end of the gun a water inlet pipe 20 is screw-threaded into a boss 21. This 20 pipe is provided with a customary valve, or stop off 22.

The action of the plunger 9, is such that when 25 water from the pipe 20 is to be supplied to the pocket or hole 12, said hole is in alignment with the opening through said pipe, as shown in Fig. 4.

4. When said charge of water is to be dropped into the drip pipe 17, said plunger is moved toward the drip pipe until the hole 12 is directly over the opening through said drip pipe, as shown in 30 Fig. 5, from whence it drops directly upon the heating chamber.

The plunger of the gun is reciprocated by means of a lever 23 operative on a pintle 24 at the outer end of a bracket 25, attached to the 35 head of the vapor generating drum B. The lower end of the lever is connected at its outer extremity of a connecting rod 26, of a governor eccentric 27. The upper end of the lever, is formed with a head having an arc-shaped slot 40 28, through which a small pin 29 projects from the plunger extremity. The arrangement of the slot in relation to the pin 29, is such, that when motion from the engine is running with a maximum of speed, the gun will drip water into the generator, but when below speed the pin 29 will 45 simply ride in the slot 28, without affecting the plunger 9.

The governor has the usual eccentric, and 50 about the same is the customary strap, and the variation of the thrust of the rod is governed by the springs which control the weights 10, in the usual manner. And from the governor, the amount of water in the piston 9, is controlled.

This governor is of the usual rotating ball type 55 having the customary vertical operating control stem as shown.

Attached at the rear head of the vapor generating drum, a heat regulated thermostat 31, is affixed. This thermostat is amenable to fluctuations 60 of heat produced by the vapor generating drum, and is for the purpose of regulating electric current for causing the carbons 6 to flame in the heat generating chamber D.

Extending from below the drum, is a bracket 65 32 through which a pintle 33 supports a lever 34 having an arcuate insulated upper end. This lever has an offset 35 engaging with the thermostat, and is amenable to oscillation, from shrinking and expansion of said thermostat. The head 70 of this lever carries a contact plate 37 which is insulated from the lever head, and the bracket 36 on its under side carries an inverted insulator shoe 38 through the upper portion of the bracket 75 and shoe, two spool insulators 39 project, the

heads of which seat on the upper portion of the bracket.

Through each of the spool insulators, the ends 80 of the electrical conducting wires 6, are fitted. The ends of these wires are adapted to contact with the inlaid plate 37, when electrical current is carried to the heating carbons 5. Should the heat of the drum rise above a predetermined temperature, the thermostat 31, would cause the lever 34, to move on its pivot and break the contact of the plate 37 at one end with the end 85 of one of the electrical conducting wires 6, and reduce the heat of the heat conducting chamber D. A reverse or reacting movement of the thermostat, especially to the extent of causing the plate 37 to draw beyond the same wire, would cause a similar occurrence. Electrical current is supplied to the carbons 5, only when both wires 90 6 are in contact with said plate.

In the drawings I have shown two sets of heating elements, in the form of electrically heated carbons, it will be understood however, that one or more heating elements could be used as the exigency of the case might require. As shown, the carbons 5 enter the heat producing chamber 100 through internally grooved spool insulators 40. The grooves are formed for purposes of ventilation, between longitudinal ribs 41 on the interior of the spools.

In the mechanism shown, internally screw-threaded flanges 42 and 43 are directly attached to both of the outer surfaces of the heating chamber and vapor generating drum at coincident oppositely disposed positions. Screw-threaded from the outer flanges 43 into the 110 flanges 42, screw threaded thimbles 44 are fitted, and seated within these open ended thimbles the carbon spool insulators 40 are seated.

In carrying out my invention, I am aware that 115 certain modifications could be resorted to, without departing from the intent and spirit of what I have herein illustrated and set forth, and I reserve the right to arrange and construct the various elements that enter into my invention, as compatible with what I claim as new and desire to secure by Letters Patent:—

1. In a mechanism as herein set forth, the same comprising a vapor generating drum, a heating chamber wholly enclosed within said vapor generating drum, a water gun operable on the 125 top of said vapor generating drum, a water dropping pipe leading from said gun into said vapor generating drum and in close proximity to the top of said heating chamber, a water supply pipe leading to said gun, an exit opening from said vapor generating drum, and means for automatically controlling the water from said gun into said vapor generating drum coordinate with means for controlling heat to said heating chamber.

2. In a mechanism as herein set forth, the same comprising a heating chamber, a vapor generating drum wholly enclosing said heating chamber, an exit opening from said vapor generating drum, 140 a water intake pipe, a water gun connected with said water intake pipe on the top of said vapor generating drum, a water dropping pipe leading from said gun into said vapor generating drum in close proximity to the top of said heating chamber, a thermostat attached to said vapor generating drum and amenable to heat from said drum, means operable from said thermostat for controlling heat to said heating chamber, and means for controlling water from said gun into said 145 150

vapor generating drum and onto said heating chamber.

3. In a mechanism as herein set forth, the same comprising a cylindrical vapor generating drum, 5 a heating chamber wholly enclosed within said vapor generating drum, said vapor generating drum having an exit opening and a water inlet pipe leading from its exterior in close proximity to the top of said heating chamber, 10 means for controlling water leading through said water inlet pipe, said heating chamber being connected to said vapor generating drum by longitudinally disposed oppositely arranged hollow open ended thimbles leading from the exterior 15 of said vapor generating drum into said heating chamber, said thimbles being hermetically sealed within said vapor generating drum, heating carbons leading through said thimbles into said heating chamber, electrical conducting wires 20 leading to said carbons, means for conducting electrical current over said wires, means including a thermostat attached to said vapor generating drum for controlling electrical current to said carbons, said means for controlling water acting 25 coordinate with means for controlling electrical current flowing over said wires to said carbons, said vapor generating chamber having an exit opening therefrom.

4. In a mechanism as herein set forth, the 30 same comprising a vapor generating drum having both an exit opening and a water intake pipe,

a heating chamber wholly carried within said drum and spaced therefrom on all portions, said heating chamber having annular convolutions, supporting members having central longitudinal openings therethrough leading from the exterior 80 of said vapor generating drum into said heating chamber in oppositely disposed positions in horizontal alignment and longitudinally thereof, means to heat said chamber through the openings through said supporting members, and 85 means to intermittently pass water through said water intake pipe.

5. In a mechanism as herein set forth, comprising a vapor generating drum, a concentrically disposed heating chamber suspended within said drum, an exit opening to said drum and a vapor producing intake pipe leading into said drum, screw-threaded flanges attached to both said drum and heating chamber at diametrically opposite points on the outer surfaces of both said drum and chamber, centrally open ended exteriorly screw-threaded thimbles connecting opposite flanges, spool insulators having longitudinal openings extending through said thimbles, carbons extending from the exterior through said 100 insulators and into said heating chamber, electrical conducting wires attached at the outer ends of said carbons, and an electrical source of supply for feeding said wires.
